UNITED STATES PATENT OFFICE.

WILLIAM W. MACFARLANE, OF PHILADELPHIA, PENNSYLVANIA.

ELECTRICAL CONTACT-SHOE.

1,261,578.

Specification of Letters Patent.

Patented Apr. 2, 1918.

Application filed April 20, 1916. Serial No. 92,420.

To all whom it may concern:

Be it known that WILLIAM W. MACFARLANE, citizen of the United States, and resident of Philadelphia, in the county of Philadelphia and State of Pennsylvania, have invented certain new and useful Improvements in Electrical Contact-Shoes, of which the following is a specification.

The device of this invention consists of a contact shoe for the purpose of taking electrical currents from a rail or other similar conductor against which the shoe is held in constant contact. This shoe may be carried upon the engine or any of the cars of a rail-way train,—if it is to operate upon railway tracks, and is firmly held in place by some suitable means of support attached to the vehicle which is carrying it.

The shoe consists of a hard protecting casement of steel or other metal having high wearing and resisting qualities. Into this steel frame or casement copper is cast or otherwise placed so that it will be exposed on the contact surface of the shoe through apertures of any desirable form or shape but in such a manner that the friction of contact is borne by the steel and not by the copper. By this device there is combined the strength and durability of the steel to resist the constant friction of contact together with the great conductive power of the copper. This shoe is particularly adapted to taking and conducting electrical currents from the rails of an ordinary railway track into electrical apparatus carried upon an engine or railway car and used for purposes of signaling, telephoning, automatic train control, and may be used to advantage for picking up driving and propelling currents from third rails, etc. The invention of this application has met the problem of combining strength and durability with the lowest resistance and its usefulness and novelty is apparent.

The invention will be best understood from a consideration of the following detailed description taken in connection with the following drawings, all of which form a part of this specification. In the figures of the drawing the identical parts are marked with the same numbers.

Figure 1 is a view in perspective of one of the shoes contemplated by this invention.

Fig. 2 is a side elevation partly in section of the same.

Figs. 3 and 5 are views of the contact sur-

face of the shoe showing two plans for bringing to the contact surface a metal of good conducting properties. The inventor does not confine himself to any form of aperture through which this conducting metal reaches the contact surface.

Fig. 4 is a cross section of the shoe illustrating the same as Fig. 3.

In Fig. 1 1 represents the hard metal protector or casement preferably constructed of steel. 2 represents some suitable means of support to be connected with the vehicle carrying the shoe. These may very properly be hinged or pivoted as shown in the drawing, and are designed to hold the shoe in its place on the track. The shoe is prevented from moving at right angles to and is held in close contact with the track by flat springs 3 and 4 which are attached to cap 5. The edges of this cap extend down over both sides of the shoe. The copper part of the shoe is represented by 6 which in Fig. 1 shows the upper surface of the copper. In Fig. 2 this copper body is shown extending to the contact surface at 7 and 8. The conductors which carry the current from the shoe into the apparatus on the car are attached to copper posts 11 and 12 which are all cast as a part of 6. Over the posts 11 and 12 are fitted collars which are attached to cables or other conductors for carrying the current to the desired apparatus. These collars are represented by 9 and 10 in Fig. 2, and a rail of the track is represented by 13 and the figure shows how contact is made at the contact surface.

Fig. 3 represents the top view of a portion of the shoe and shows how the copper conductor is exposed at points 14, etc., for the purpose of contact with the rails, being protected from excessive wear by the incase-ment of hard metal 1.

Fig. 4 is a cross section of the same illustrating a similar placing of the copper contact.

Fig. 5 shows another plan by which the copper may be brought to the surface of contact as shown at 15, 16, etc. This inventor however does not confine himself to any special shape of aperture or any special way of putting the copper into the shoes.

As this metallic shoe is carried by the moving vehicle in contact with a rail or other surface from which it is desired to conduct an electrical current, the current will be picked up by the copper contacts at

the contact surface and carried by the copper to the copper posts 11 and 12 and from there through the cables or other conductors to any desired point. The steel casement 5 without the copper contacts would not serve as a good conductor to pick up the current but its purpose in this device is of high importance and is to save the copper or soft contact metal from wear by constant friction. The shoe is capable of adjustment by its suitable means of support and springs 3 and 4. It can be adapted to fit any desired position. In an electrical system for automatic train control and signal device, this 10 inventor has found the shoe particularly suitable for carrying on the engine of a railway train immediately back of the wheels so that the wheel in front of the shoe will keep the track continually clear of snow or other obstruction.

20 What I claim is:—

1. A contact shoe comprising: a wear-resisting member having a surface arranged for sliding engagement with a conductor, 25 and a conducting member having an integral projection extending through said wear-resisting member to the conductor-engaging surface thereof.

2. A contact shoe comprising: a wear-resisting member having a conductor-engaging surface, and a conducting member having a plurality of projections extending through the wear-resisting member to the conductor-engaging surface thereof.

3. A contact shoe comprising: a wear-resisting member having a surface of substantial area arranged for sliding engagement with a conductor, and a conducting member having a plurality of projections extending through the wear resisting member to the conductor engaging surface thereof.

4. A contact shoe comprising: an elongated wear-resisting member having a sur-

face arranged for sliding engagement with a conductor, and a conducting member having projections extending through the wear-resisting member at a plurality of points intermediate the ends thereof. 45

5. A contact shoe comprising: a wear-resisting member having a container-shaped opening in one face thereof and having the opposite face arranged for sliding engagement with a conductor, said wear-resisting member having perforations extending between said opening and said conductor-engaging surface, and conducting material filling said opening and said perforations, whereby the conducting material has projections extending through the wear-resisting member to the conductor-engaging surface 55 thereof.

6. A contact shoe comprising: a wear-resisting member having a generally grid-shaped formation and a conductor engaging surface, and conducting material filling the 65 interstices of said wear-resisting member, whereby the conducting material will engage the conductor for a substantial area and be protected from wear.

7. A contact shoe comprising: an elongated wear-resisting member, links pivoted to opposite ends of said member for attaching said member to a vehicle, said wear resisting member having perforations extending therethrough to the conductor 75 engaging surface thereof, and a conducting member having projections extending through said perforations to engage said conductor.

Signed at Philadelphia, in the county 80 of Philadelphia and State of Pennsylvania April, A. D. 1916.

WILLIAM W. MACFARLANE.
